GARMENT HANGER

Adolph J. Fussenegger, Louisville, Ky.

Application December 3, 1934, Serial No. 755,789

5 Claims. (Cl. 211—86)

My invention relates generally to garment hangers, and particularly to a trousers or skirt hanger especially adapted to be permanently mounted on the posts or sides of beds or on a closet or other rigid support, and an important object of my invention is to provide a hanger of the type indicated which can be easily collapsed and swung out of the way when not in use and is as readily extended and swung into position for use.

Another important object of my invention is to provide a garment hanger of the type indicated above which can be readily adapted for mounting on different objects, and which is strong and simple in structure and relatively inexpensive to manufacture and install.

Another important object of my invention is to provide a garment hanger of the type indicated above which holds the trousers or skirt in such a position that wrinkling and false creasing thereof is avoided.

Other objects and advantages of my invention will be apparent from a reading of the following description in connection with the drawings, wherein for purposes of illustration I have shown a preferred embodiment of my invention.

In the drawings:—

Figure 1 is a general elevational view showing the embodiment installed on a rigid support such as the head of a wooden bedstead.

Figure 2 is a top plan view of the embodiment. Figure 3 is a top plan view of the mounting bracket shown in Figure 1.

Figure 4 is a transverse vertical sectional view taken through the lower part of the embodiment as shown in Figure 1 showing the pivotal or swinging mounting.

Figure 5 is a transverse vertical sectional view taken through Figure 2 approximately on the line 5—5.

Figure 6 is a plan view of an insert.

Figure 7 is an end view of the insert made up.

Figure 8 is a side elevational view of a modified form of mounting bracket.

Figure 9 is a horizontal sectional view taken through Figure 8 approximately on the line 9—9.

Referring in detail to the drawings, the numeral 5 refers generally to a block of wood or other similar suitable material which is generally rectangular in form and in cross section and has near one end thereof two opposite sides formed with vertical semi-circular depressions 6, 7 which are connected by a pair of bores 8 which receive mounting screws 9 in a position in which the heads of the screws are set back from the corre-

sponding sides of the block and extend outwardly of the opposite side of the block as when screwed into the sides of a wooden bed post or other rigid wooden support such as the head of the bed illustrated in Figure 1 and generally designated 10.

Fitted into a recess 11 in the opposite end of the block 5 is a dowel 12 which has at a point spaced upwardly from the top of the block 5 a circumferential groove 13 the sides of which form stops engageable by a locking or set screw 14 which traverses the side of the standard 15. The standard 15 has extending upwardly from its lower end the bore 16 which is of such height that when the standard 15 is telescoped onto the dowel 12, with the bore 16 receiving the dowel 12, the lower end of the standard 15 will be supported above the top of the block 5, so that the standard 15 may freely pivot on the dowel 12. The dowel 12 sufficiently closely fits the bore 16 to prevent wobbling of the standard even when weighted by garments when in use. The locking screw 14 prevents inadvertent separation of the standard from the dowel and also acts as a theft-proof arrangement.

The standard 15 is preferably rectangular in cross section and has opening through its top the transversely spaced vertical recesses 17 and 18 which are connected by the slot 19. In the recess 17 works a plunger 20, while in the recess 18 works a catch 21 which is normally projected to the upward position shown in Figure 5 by a spring 22 interposed between the lower end of the catch 21 and the bottom of the recess 18. The upper end of the catch 21 is beveled as indicated, the lower end of the bevel facing toward the side of the standard at which the hanger arm to be described is pivoted. A bar 23 sliding in the slot 19 connects the catch 21 with the plunger 20 so that depression of the plunger 20 by exerting pressure thereon with the finger will depress the catch 21 against the resistance of the spring 22 and release the hanger arm in a manner to be described. A finishing plate 24 having appropriate openings permitting the catch 21 and the plunger 20 to pass therethrough is fastened as indicated at 25 to the standard.

A hinge having the leaf 26 fastened to one side of the standard 15 at a point spaced below the upper end thereof has pivoted to the upper end thereof the hinge leaf 27 which is fastened to the underside of the hanger arm generally designated 28, whereby the heel of the hanger arm will abut the standard above the hinge when in extended position, and may fall to the perpendicular dotted line position indicated in Figure 1 when not in

the extended position, so as to be out of the way. A coat hanger hook 29 may be anchored in the standard 15 below and to one side of the hanger arm as indicated in Figure 1.

5 The hanger arm 28 comprises the block 30 to opposite sides of which are fastened the generally parallel arms 31 and 32 which have the inner side of their outer ends rounded as indicated at 33 to provide smooth entrance for the garments 10 to be suspended. A V-shaped keeper generally designated 34 is fastened as indicated at 35 to the upper edges of the arms 31 and 32 and to the top of the block 30 as indicated at 36, and the apex part of the keeper is formed with an eye or 15 loop 37 which is adapted to engage the beveled face of the catch 21 as the hanger arm is pushed upwardly into the extended position and engage over and back of the catch so as to be held in the extended right angular position indicated in 20 Figure 1. Depressing of the plunger 20, causing depression of the catch 21 will release the loop 37 and permit the arm 28 to fall to the dotted line position shown in Figure 1.

For holding the waist-band part of the trousers 25 or of the skirt, for which the hanger is especially adapted, the arm 32 is provided with a pair of bowed springs 38 and 39. The outer end of the spring 38 is fitted in a slot in the inner face of the arm 32 and anchored therein by means of a 30 screw 40. The inner end of this spring has a rounded part 41 which loosely slides and works in a depression 42 in the inner side of the arm 32.

The spring 39 has its outer end bent as indicated at 43 and inserted in a slot where it is held by a 35 screw 44 at the outer end of the arm 32. The inner end of the spring 39 has a rounded part 45 which slides and works loosely in a recess 46 in the inner side of the arm. In the initial position of the springs they are sprung against the inner 40 side of the opposite arm 31. The waist-band part of a skirt or trousers is to be inserted by holding the opposite ends of the waist-band and drawing this part of the garment between the outer ends 33 of the arms and between the springs and the 45 inner side of the arm 31 until the garment is in a position to be held suspended by engagement of the springs with one side thereof and engagement of the inner side of the arm 31 with the opposite side thereof. It will be obvious that as the springs 50 are compressed by the presence of the garment the rounded ends of the springs will move in the recesses 42 and 46. If desired, the arms 31 and 32 may be formed of such material as to be somewhat yieldable though relatively rigid compared 55 to the spring character of the springs.

When it is desired to mount the device of the invention on the round post of a metal bed or other similar round post, I substitute for the block 5 the bracket 5a which consists of a shorter 60 tapered block 47 having the dowel 12a rising therefrom having the locking slot 13a, the standard 15 being engageable with the dowel 12a exactly as in the case of the dowel 12 and the screw 14 of the standard being engageable in the 65 locking slot 13a in the same manner as is illustrated in Figure 4 and already described.

The left hand end of the block 47 has a recess 48 in which is set a segment 49 forming part of a compressible spring band generally designated 50 and having a perforated ear 51 one end which receives the headed end 52 of the clamping screw 53 whose threaded end passes through a hole in the ear 54 of the main band section 55 whose opposite end reaches almost to the ear 51 and 75 within the band section 49. A nut 56 on the

threaded end of the bolt 53 is adapted to be screwed up to bring the ears 51 and 54 toward each other and clamp the band around the bed post or the like for securing the block 47 rigidly thereto. A sheet of felt or the like 57 is placed 5 between the band section 49 and the adjacent end of the main band section 55, and the main band section is entirely lined by a felt or similar non-scratching strip 58. The parts of the block 47 above and below the recess 48 are spaced with 10 felt pieces 59 so that engagement of these parts with the bed post or the like will not scratch the same. The main band section 55 is provided with circumferentially spaced pairs of holes 60 to receive the vertically spaced mounting and locking 15 screws 61 which traverse the block 47 horizontally and screw into blind nuts 62 in the right hand end of the block. The band 50 may be made larger and smaller simply by selectively arranging the screws 61 in the holes 60. The screws 61 hold the band section 49 and the main band section 55 connected with the block 47.

When it is desired to apply the bracket 5a to a square metal bed post or other similar square post I employ the insert which is generally designated 62 and which is composed of an elongated T-shaped sheet of felt or similar fabric material 63 on one side of which are attached longitudinally spaced segmental blocks 64 on the narrow part of the sheet and the single segmental and wider block 65 on the widest part of the sheet 63. There are four blocks in all and the curved side of the blocks is so arranged that when the insert is placed within the band 50 the felt on the inner 30 sides of the block forms a substantially perfect square which directly engages the square post in non-scratching manner when the band 50 is contracted by screwing up the nut 56.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. A garment hanger comprising a bracket for rigid mounting on a support, a vertical dowel projecting upwardly from the bracket, a standard pivotedly mounted on said dowel in axial extension thereof, a hanger arm pivoted to the upper part of the standard, and latch means on the upper end of the standard and releasably engaging a portion of the hanger arm for maintaining the hanger arm in a horizontal position, said latch means being releasable to permit said hanger arm to swing to a depressed vertical position.

2. A garment hanger comprising a bracket for rigid mounting on a support, a vertical dowel 50 projecting upwardly from the bracket, a standard pivotedly mounted on said dowel in axial extension thereof, a hanger arm pivoted to the upper part of the standard, and latch means on the upper end of the standard and releasably engaging 55 a portion of the hanger arm for maintaining the hanger arm in a horizontal position, said latch means being releasable to permit said hanger arm to swing to a depressed position.

3. A garment hanger comprising a bracket for rigid mounting on a support, a vertical dowel 60 projecting upwardly from the bracket, a standard pivotedly mounted on said dowel in axial extension thereof, a hanger arm pivoted to the upper part of the standard, and latch means on the upper end of the standard and releasably engaging 65 a portion of the hanger arm for maintaining the hanger arm in a horizontal position, said latch means being releasable to permit said hanger arm to swing to a depressed position, said hanger arm being composed of a pair of horizontally spaced members, one of said members having longitudinal springs mounted thereon and arranged to engage the opposite arm and being yieldably compressible by inserting a garment between the arms.

3. A garment hanger comprising a bracket for rigid mounting on a support, a vertical dowel projecting upwardly from the bracket, a standard pivotally mounted on said dowel in axial extension thereof, a hanger arm pivoted to the upper part of the standard, and latch means on the upper end of the standard and releasably engaging a portion of the hanger arm for maintaining the hanger arm in a horizontal position, said latch means being releasable to permit said hanger arm to swing to a depressed vertical position, said bracket comprising a block carrying said dowel, said block including means for engaging and forming a connection with a rectangular support.
5. A garment hanger comprising a bracket for rigid mounting on a support, a vertical dowel projecting upwardly from the bracket, a standard pivotally mounted on said dowel in axial extension thereof, a hanger arm pivoted to the upper part of the standard, and latch means on the upper end of the standard and releasably engaging a portion of the hanger arm for maintaining the hanger arm in a horizontal position, said latch means being releasable to permit said hanger arm to swing to a depressed vertical position, said bracket comprising a block carrying said dowel, said block including means for engaging and forming a connection with a rectangular support.
10. A garment hanger comprising a bracket for rigid mounting on a support, a vertical dowel projecting upwardly from the bracket, a standard pivotally mounted on said dowel in axial extension thereof, a hanger arm pivoted to the upper part of the standard, and latch means on the upper end of the standard and releasably engaging a portion of the hanger arm for maintaining the hanger arm in a horizontal position, said latch means being releasable to permit said hanger arm to swing to a depressed vertical position, said bracket comprising a block carrying said dowel, said block including means for engaging and forming a connection with a rectangular support.
15. A garment hanger comprising a bracket for rigid mounting on a support, a vertical dowel projecting upwardly from the bracket, a standard pivotally mounted on said dowel in axial extension thereof, a hanger arm pivoted to the upper part of the standard, and latch means on the upper end of the standard and releasably engaging a portion of the hanger arm for maintaining the hanger arm in a horizontal position, said latch means being releasable to permit said hanger arm to swing to a depressed vertical position, said bracket comprising a block carrying said dowel, said block including means for engaging and forming a connection with a rectangular support.
20. A garment hanger comprising a bracket for rigid mounting on a support, a vertical dowel projecting upwardly from the bracket, a standard pivotally mounted on said dowel in axial extension thereof, a hanger arm pivoted to the upper part of the standard, and latch means on the upper end of the standard and releasably engaging a portion of the hanger arm for maintaining the hanger arm in a horizontal position, said latch means being releasable to permit said hanger arm to swing to a depressed vertical position, said bracket comprising a block carrying said dowel, said block including means for engaging and forming a connection with a rectangular support.

ADOLPH J. FUSSENEGGER.
